UNITED STATES PATENT OFFICE.

JOHN REID, OF NEW YORK, N. Y.

FURNACE-FRONT AND VALVE MECHANISM THEREFOR.

1,333,732.

Specification of Letters Patent. Patented Mar. 16, 1920.

Application filed November 2, 1918. Serial No. 260,883.

To all whom it may concern:

Be it known that I, JOHN REID, a subject of the King of Great Britain, and residing at 30 Church street, in the city of New York,

5 in the State of New York, in the United States of America, have invented new and useful Improvements in Furnace-Fronts and Valve Mechanism Therefor, of which the following is the specification.

10 The invention relates to improvements in furnace fronts and valve mechanism therefor, as described in the present specification and shown in the accompanying drawings that form part of the same.

15 The invention consists essentially of the novel means employed, whereby efficient operation of the valve mechanism is maintained and whereby valves operate coincidentally with the movements of the feed

20 passage door.

The objects of the invention are to furnish smooth and uninterrupted operation of the air and draft system in marine and other furnaces, to insure the accessibility of the

25 parts and their convenient manipulation by the attendant, to assemble the component pieces, so as to standardize the whole with the furnace front, to eliminate the danger incident to certain draft conditions and open

30 feed door and generally to provide a serviceable, durable and easily operable valve mechanism.

In the drawings, Figure 1 is an elevation of the back plate showing the fuel passage 35 and ash pit flare in cross section and a plan of the valves and operating gear.

Fig. 2 is an enlarged detail of the valve plate and fastener parts showing the crank lugs as part of the latter and the connecting rod broken away.

40 Fig. 3 is an enlarged longitudinal sectional detail of the parts operated by the valve handle and the connecting rod, the latter broken away.

45 Fig. 4 is a cross sectional detail of the squared shaft showing the crank and connecting rod, the latter broken away.

Fig. 5 is an elevation of the furnace front plate, showing the latch bar of the fuel 50 passage door and the stop operated coincidentally with the valve handle.

Like numerals of reference indicate corresponding parts in each figure.

Referring to the drawings, the front plate 55 1 is formed with the ash pit opening 2 and fuel opening 3.

The ash pit opening 2 communicates with the furnace proper through the passage 5 and a corresponding opening in the back plate 6.

60 The fuel passage 7 leads from a corresponding opening in the back plate 6 and terminates at the fuel opening 3. The air passage 8 is between the front and back plates, and has suitable outlets through said 65 back plate. The fuel passage is surrounded by the wall 7^a and the air passage 8 by the wall 8^a. The ash pit flare 5^a completes the main frame of the furnace front, though the precise construction is not necessary for 70 the successful operation of this invention.

The catch 9 is formed adjacent to the door opening 10 at one end thereof and the hinge members 11 at the other end.

The door 12 with corresponding hinge 75 members 13 is held to the hinge members 11 by the rod 14 and closes the door opening 10.

The latch bar 15 is secured to the center of the door 12 by the pivot 16 and is adapted 80 to lock in the catch 9 and beyond said catch is formed into the hook offset 17 for opening purposes.

The stop 18 is secured to, or forms part 85 with the square shaft 19, the latter terminating in the threaded end 20. The bushing 21 having a square hole corresponding to the shaft 19 is mounted thereon and journaled in the orifice 22 in the front plate 1 adjacent to the latch bar 15, so that in turning, 90 the stop 18 moves over and beyond the end of the latch bar 15.

The handle 23 is formed at the end of its lever section 24 with a square orifice 25 corresponding to the square shaft 19 and is 95 mounted thereon outside of the bushing 21. The lever section 24 travels over an arc-shaped track 26, at each end of which are the stops 27 and 28, said track and said stops being preferably cast with the front plate 1. 100

The crank 29 is mounted on said square shaft 19 inside the front plate 1, which it abuts, and has the forked end 30 forming pivot bearings.

The nut 31 is mounted on the threaded 105 end 20 and the spiral spring 32 encircles the shaft 19 between the nut 31 and the crank 29, consequently the shaft 19 is constantly drawn inwardly, which maintains the bushing in its journaling and keeps the valve 110 handle close to the front 1.

The connecting rod 33 is pivotally secured

in the forked end 30 of the crank 29 and is formed with the turnbuckle 34.

The shaft 35 is journaled beneath the door opening 3 and extends through the air passages 8 and carries the plates 36 and 37 forming valves which are rigidly secured to said shaft.

In securing the plate 36 to the shaft the block 38, longitudinally grooved at 39 to receive the shaft, is placed against the underside of the plate 36 and the cover plate 39 against the upper side immediately over said block 38, so that the bolt holes 40 are in alignment with the bolt holes 41. The bolts 42 are then inserted through cover plate 39, valve plate 36 and block 38, engaging the shaft 35 in the grooves 43, and are fastened by the nuts 44.

A similar block 45 is placed against the bottom of the plate 37 and is held by the bolts 46 also engaging grooves 47 in the shaft and extending through the cover plate 48, said cover plate 48 having the parallel lugs 51 and 52 forming pivot bearings for the lower end of the connecting rod 33.

The valve plates 36 and 37 are further secured to the shaft 35 by the U-bolts 53 and nuts 54, said bolts extending through the clamping plates 55.

30 In the operation of this invention, the valve plates as shown control the flow of air to the fire box, otherwise the draft for stimulating the fire and bringing the fuel to a state of incandescence. These plates, 35 being fixed to the shaft as shown and the latter journaled so as to project through the air passages, shut off the said passages, when turned to an oblique position against the walls.

40 The connecting rod attached to the crank formed by the valve fastener cover with the parallel lugs is operated by the movement of the valve handle traveling over the arc-shaped track on the furnace front. The 45 swinging of this handle to one end of the track closes the valves and to the other end opens the valves, as will readily be seen by reference to the drawings and the detailed description of the parts hereinbefore.

50 The swinging of the handle is accompanied by the rotation of the stop for the door latch and in turning the crank shaft for closing the valves, the stop moves away from said latch leaving the door free to 55 open, but so long as the valves are in their open positions, the stop will stay in front of the latch bar and frustrate any attempt to open the door, therefore no tongue of flame will reach out of the furnace door opening, which is a great protection to the stokers, because if the draft was maintained during the door opening act, the chances are 60 the stoker would be badly burned.

In this invention the course of the air is 65 precisely the same as in many known types

of forced draft furnace fronts particularly of the "Scotch" type and briefly it may be pointed out that the air is forced in at 60 and 61 above the side valves 36 and 37 respectively and flows through the ports 70 opened by said valves into the ashpit and on to the underside of the grate in the same manner as any air draft. The top valve closes ports to the air chamber around the fuel passage and flows to the baffles and 75 through the holes to the fire box as customary.

Various changes may be made in the construction of the several parts and their arrangement, so long as they remain within 80 the scope of the claims for novelty following.

What I claim is:—

1. In a furnace front and valve mechanism therefor, a main frame comprising a 85 front plate, a back plate, a passage wall having a fuel passage and spacing and connecting said plates and an ash pit flare, said plates forming air passages to the ash pit, pivoted valves with said wall dividing the 90 interior between said plates into upper and lower portions, means for connecting the valves for transmitting motion from one to the other, a crank shaft journaled in the upper portion of said front plate above the 95 plane of the said valves and having an operating handle at its outer end, a crank on said crank shaft, a rod extending downwardly from the crank and operatively connected to the same and to one of the valves 100 for opening and closing the latter, a door closing the front end of the said passage, a latch bar pivotally secured on said door, and a stop rigid with the crank shaft and movable to and from a position in front 105 of the latch bar and arranged to lock the latch bar coincidentally with the opening of the valves.

2. In a furnace front and valve mechanism therefor, a main frame comprising a 110 front plate, a back plate, a fuel passage wall spacing and connecting said plates and an ash pit flare, said plates forming air passages to the ash pit, a valve shaft journaled below said passage wall, valves fixedly 115 mounted on said shaft and with said passage wall dividing the interior of the front into upper and lower portions, a fuel door, a latch bar for said fuel door, a crank shaft journaled in the front plate above the plane 120 of said valves, cranks mounted on the crank shaft and the valve shaft, a rod operatively connecting the said cranks for opening and closing the valves, an operating handle mounted on the crank shaft, and a rotating stop carried by the crank shaft 125 and engaging and disengaging the latch bar and arranged to lock the latch bar when the valves are open and release the latch bar when the valves are closed.

3. In a furnace front and valve mechanism therefor, a main frame comprising a front plate, a back plate and a fuel passage wall having a fuel passage, a door to said passage, a latch bar mounted on said door, a rotatable stop engaging the latch bar, a square shaft extending inwardly through the front plate and carrying the said stop and provided with a handle, a bushing mounted on said shaft and journaled in the front plate, a crank mounted on said square shaft and spring-held in place, a valve shaft journaled at right angles to the aforesaid shaft, and valves secured to said shaft and arranged when closed to cut off the draft, a crank operatively connected with one of the valves, and a rod connecting the cranks for opening and closing the valves, the said stop being arranged to engage the latch bar when the valves are open and to release the latch bar when the valves are closed.

4. In a furnace front and valve mechanism therefor, a main frame comprising a

front plate, a back plate, a fuel passage 25 wall having a fuel passage, said plates forming air passages to the ash pit, a door closing said fuel passage, a latch bar mounted on said door, a valve shaft journaled below said fuel passage, valves mounted on said shaft and operating in the air 30 passages, a square crank shaft journaled in the front plate above the plane of the valve and adjacent and in proximity to said latch bar, a stop carried by the crank shaft 35 and movable into and out of engagement with the latch bar and arranged to lock the latch bar when the valves are open and to release the latch bar when the valves are closed, a crank mounted on said crank shaft, 40 a nut screw threaded on the crank shaft, a spring between said nut and crank, and a rod operatively connecting the crank shaft and the valve shaft.

Signed at New York city this 29th day of 45 October, 1918.

JOHN REID.
